(57) **CLAIM**

The ornamental design for a driver chassis, as shown and described.

DESCRIPTION

FIG. 1 is a front perspective view of a driver chassis showing my new design;

FIG. 2 is a right side view of the driver chassis;

FIG. 3 is a left side view of the driver chassis;

FIG. 4 is a front view of the driver chassis;

FIG. 5 is a back view of the driver chassis;

FIG. 6 is a top view of the driver chassis;

FIG. 7 is a bottom view of the driver chassis;

FIG. 8 is a front perspective view of the driver chassis; and,

FIG. 9 is an exploded view of the driver chassis.

The broken lines of the Figures illustrate environmental structure and portions of the driver chassis that form no part of the claimed design.
